ABSTRACT

A constant current source is utilized in the bias circuit to prevent variations in the driving impulses of an electronic timepiece resulting from battery voltage decay.

**CIRCUIT ARRANGEMENT FOR THE DRIVE OF A
CLOCKWORK MECHANISM
REGULATOR-OSCILLATOR OF A TIMEPIECE**

BACKGROUND OF THE INVENTION

This invention relates to a circuit for the drive of a clockwork mechanism regulator-oscillator of a time-piece, preferably a watch. The circuit includes an electronic amplifier, preferably a semiconductor amplifier, that is controlled by a voltage produced by the relative movement between a magnetic system and a control element and delivers current impulses acting in a driving manner on the clockwork mechanism regulator-oscillator. These impulses flow through a driving element and a switch element is connected to the supply voltage source of the amplifier for the production of a bias voltage for application to the input circuit of the amplifier.

Circuit arrangements of the above-mentioned type are known where a bias voltage is produced by circuit elements, where the bias voltage influences the amplifier input and where the switch elements are supplied by the current source supplying the amplifier. Thus, for example, a circuit is known in which a capacitor is located in series with a control coil in the input circuit of a transistor, which capacitor is connected with the source of current supplying the amplifier by way of a resistor through which the capacitor is charged. In this known circuit, the charging current changes with the voltage of the battery, i.e., the charging current decreases whenever the battery voltage is reduced after a period of time through usage. As a result, the input bias voltage is also influenced and the driving current decreases with the decreasing battery voltage. The constancy of the timing impulses is thus unfavorably influenced.

An object of this invention is to provide a novel circuit of the abovementioned type in which the driving current is not changed as a result of a change of the supply voltage. This object is achieved according to the invention by the connection of the circuit element for the production of the bias voltage through a constant current circuit to the supply voltage.

Another object is to provide a novel transistorized, constant current network, preferably a field effect transistor circuit.

Through the constant current circuit of the present invention, the current producing the bias voltage is kept constant within a certain voltage range and as a result changes in the bias voltage on the basis of fluctuations of voltage of the source of the supply voltage are eliminated. Thus the precision of a time-keeping device, e.g., an electric watch, is influenced favorably.

A capacitor connected in a known manner in series with the control element such as a control coil is preferably used as the circuit element for producing the bias voltage. At the same time, a regulator amplifier controlled in dependence on the amplitude of the clockwork mechanism regulator-oscillator is also preferably provided to influence the bias voltage in which event an especially good constancy of the clockwork mechanism regulator-oscillator results.

The invention is hereinafter explained in more detail in the following paragraphs with reference to the drawings and in a few embodiments given by way of examples.

THE DRAWINGS

FIG. 1 is a schematic circuit diagram of the drive of the clockwork mechanism regulator-oscillator of a time-keeping electric device to which the present invention is applicable;

FIG. 2 is a schematic circuit diagram of an exemplary constant current circuit according to the present invention;

FIG. 3 is a schematic circuit diagram of a second embodiment of the constant current circuit of the present invention;

FIG. 4 is an elevation of a clockwork mechanism regulator-oscillator relative to the coils of the circuit of FIG. 1; and,

FIG. 5 is an elevation in section taken through lines V—V of FIG. 4.

THE DETAILED DESCRIPTION

20 The driving circuit shown in FIG. 1 contains a main transistor T_1 , in the base-emitter circuit of which lies a control element such as a capacitor C in series with the illustrated coil L_1 influenced by the clockwork mechanism regulator-oscillator. The driving coil L_2 is connected in series with a direct current source U_0 for d.c. voltage in the base-collector circuit of the transistor T_1 . The coils L_1 and L_2 may be disposed in a known manner coaxially near one another and may also be wound concentrically relative to one another.

25 In order to suppress feedback oscillators occurring in the event of close coupling, a neutralizing capacitor C_N may be provided in the embodiment given by way of example. Naturally, it also is possible to use other neutralizing elements to suppress the feedback oscillations. A charging impedance 12 may be connected at one end 11 to the positive pole of the source U_0 of d.c. voltage and at the other end 10 to the base electrode of the transistor T_1 .

30 The coil arrangement comprising coils L_1 and L_2 is preferably fixedly disposed while a permanent magnet system provided on the clockwork mechanism regulator-oscillator is moved relative to the coils. The magnet system moved by the clockwork mechanism regulator-oscillator basically can be of any type. Preferably a magnet system having two air gaps is used, which receive the sides of the coils in the rest position of the clockwork mechanism regulator-oscillator and which are permeated by the magnetic fluxes oppositely and perpendicularly to the plane of the coil.

35 The method of operation of such a driving circuit arrangement is known per se. Note that the capacitor C is charged by way of the impedance 12 as a result of which the base electrode of the main transistor T_1 is positively biased so that a base-to-collector current flows. Even very small control voltages in control coil L_1 are sufficient to alter the base-to-collector current of the transistor T_1 as a result of which the clockwork mechanism regulator-oscillator will obtain driving impulses. With an increasing oscillation amplitude, the voltage induced in control coil L_1 becomes higher and gradually capacitor C is changed in its charge via the base-emitter circuit of the transistor T_1 as a result of which the bias of the base electrode is changed.

40 The collector-emitter circuit of a regulating transistor T_2 is connected in parallel with the capacitor C . This regulating transistor T_2 may contain in its input circuit a regulating coil which, as in the case of the em-

bodiment shown by way of example in FIG. 1, may be at the same time the control coil L_1 for the main transistor T_1 . The coil L_1 is connected in series with the driving coil L_2 of the main transistor.

An induction voltage depending on the amplitude of the clockwork mechanism regulator-oscillator (not shown) is produced in the regulating coil L_1 which reaches the input threshold voltage of the regulating transistor T_2 so that the latter is put into a conductive state at, for example, 200° in the case of watches that can be worn. As a result of this, the capacitor C is partly or wholly discharged and thus the bias voltage of the base electrode of the transistor T_1 is influenced. Where the control coil L_1 is used to control both the main transistor T_1 and regulating transistor T_2 , a polarity of the a.c. voltage produced in the control coil may be used for control of the main transistor T_1 and the oppositely polarity voltage used for control of the regulator transistor T_2 , i.e., control transistor T_2 is blocked, for example, whenever main transistor T_1 is triggered and vice versa.

A constant current circuit 12 may be connected between the d.c. source U_0 of the supply voltage and the capacitor C , by means of which the capacitor C charging current is kept essentially constant independently of the voltage of the source U_0 , so that changes of the bias voltage of the transistor T_1 as a result of the aging of the battery U_0 are eliminated to a certain extent.

The circuit of the constant current device 12 connected between points 10 and 11 may be of any kind so long as the charging current is kept mostly constant. For example, a constant current network can be used as shown in FIG. 2. This network may contain two transistors T_3 , T_4 , a resistor R_2 connecting the base electrodes of the transistors, resistors R_1 and R_3 in the emitter electrode circuits and diodes D_1 and D_2 connected in series in the collector electrode circuits.

The constant current circuit 10 is preferably formed by the circuit shown in FIG. 3 with a field effect transistor 15 and a resistor R_5 .

The circuit of the invention can be used in the case of all driving circuits for clockwork mechanism regulator-oscillators provided for self-starting, in which circuits a bias voltage is produced in the input circuit of the driving transistor. The circuit arrangement according to the invention preferably is used where a bias voltage capacitor is provided.

For further stabilization of the voltage of the output circuit, there can additionally be used known circuit arrangements, for example, diode boosting connections.

With reference to FIGS. 4 and 5, the reference number 20 designates the shaft of a clockwork mechanism regulator-oscillator in the form of a balance wheel and

disks 21 and 22 are made of magnetically conductive material. Permanent bar magnets 23-26 are provided. The spiral spring 27 for the balance wheel is attached at 28 and the coils L_1 and L_2 may be those schematically shown in the circuit of FIG. 1.

The present invention may be embodied in other specific forms without departing from the spirit or essential characteristics thereof. The presently disclosed embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed is:

1. In a circuit for the drive of a clockwork mechanism regulator-oscillator of a time-keeping device with an electronic amplifier controlled by a voltage produced by a relative movement between a magnet system and a control element which delivers current impulses acting through a driving element in a driving manner on the clockwork mechanism regulator-oscillator, the improvement comprising a constant current device connected to the power supply of the amplifier and including a regulating amplifier controlled in dependence on the amplitude of the clockwork mechanism regulator-oscillator for the purpose of influencing the bias voltage of the amplifier.

2. The circuit according to claim 1 wherein the constant current device includes a transistor.

3. The circuit according to claim 2 wherein the transistor is a field effect transistor.

4. The circuit according to claim 1 wherein a capacitor is connected in series with a control coil for production of the bias voltage.

5. The circuit according to claim 4 including a regulating amplifier controlled in dependence on the amplitude of the clockwork mechanism regulator-oscillator for the purpose of influencing the bias voltage.

6. The circuit according to claim 5 wherein the control element and the driving element are induction coils and wherein one of said coils is in the circuit of the main amplifier and the regulating amplifier.

7. The circuit according to claim 6 wherein both the control coil and the driving coil of the main amplifier are in the input circuit of the regulating amplifier.

8. The circuit according to claim 5 including a connecting element responsive to a magnetic field for influencing the amplitude of oscillations.

9. The circuit according to claim 1 including a connecting element responsive to a magnetic field for influencing the amplitude of oscillations.
